HYDRAULIC SYSTEM FOR BORING MACHINES AND THE LIKE

William D. Schmidt, Worcester, Mass., assignor to The Heald Machine Company, Worcester, Mass., a corporation of Massachusetts

Application July 23, 1931, Serial No. 552,625
Renewed July 15, 1936

29 Claims.

(Cl. 77—3)

The present invention relates to hydraulic systems for use in automatic machines for performing boring or similar operations and is especially directed to hydraulic systems which are arranged for performing operations on successive work-pieces automatically.

The principal object of the present invention is to provide a substantially universal system for controlling the various movements of a machine in order to permit the desired operations of the machine to be performed automatically. According to the present invention which is disclosed in connection with a multiple head boring machine, a reciprocating carriage is arranged to procure a relative movement between a tool and workpiece, the rate of movement of the carriage being automatically controlled and varied so that the carriage may be moved rapidly when the tool and work are not in operative relation and so that the carriage may be moved at a relatively slow rate while the tool and work are in operative relation. The machine also permits the operation of the tool to be controlled automatically, the said tool being actuated only during the cutting stroke on the work, and being brought to rest as soon as the cutting stroke is completed. The machine is further constructed in such a manner that the carriage may be brought to rest in any desired position of travel as, for example, at the completion of each boring operation.

Especially in boring or turning machines in which the workpiece is carried past the tool during the boring operation and is then withdrawn from operative position, the rotating tool describes a spiral or helix on the finished surface during the separation of the workpiece from the tool. In order to avoid the spiral cut, the tool is brought to rest automatically at the end of the boring operation so that the subsequent withdrawal movement of the workpiece from the tool leaves only a single straight line along the finished surface, the straight line being much less objectional than the spiral cut on the finished surface.

In order that the tool may be brought to rest before the withdrawal movement of the workpiece from the tool it is desirable to provide for a predetermined dwell of the carriage carrying the workpiece at the end of the carriage movement so that the tool will not be rotating during the withdrawal movement. This dwell in the carriage movement is obtained by the use of a pilot valve which controls the main valve a predetermined

period subsequent to the shifting of the pilot valve by the carriage movement.

During the setting up of the machine, it is desirable to reciprocate the carriage independently of the operation of the remainder of the machine elements and the present invention is arranged to permit the rotary tools to remain stationary during the reciprocation of the carriage or, if desired, to be continuously actuated regardless of the movements of the carriage. Other objects and advantages of the invention will appear from the following detailed description taken in connection with the accompanying drawings in which—

Fig. 1 is a front elevation of a boring machine embodying the invention.

Fig. 2 is a plan view of the machine of Fig. 1.

Fig. 3 is an end elevation of the machine as seen from the left of Fig. 1.

Fig. 4 is a side elevation of the control mechanism.

Fig. 5 is a plan view partly in section of a portion of the mechanism of Fig. 4.

Fig. 6 is a fragmentary elevation of the mechanism for controlling the speed of the carriage.

Fig. 7 is a section along the line 7—7 of Fig. 4.

Fig. 8 is a section along the line 8—8 of Fig. 4.

Fig. 9 is a section along the line 9—9 of Fig. 4.

Fig. 10 is a section along the line 10—10 of Fig. 4.

Fig. 11 is a fragmentary sectional view of one of the valves for controlling the speed of the carriage.

Fig. 12 is a diagrammatic view of the hydraulic control system.

Fig. 13 is a diagrammatic view of the reversing lever and the mechanism for stopping the movement of the table, the parts being in inoperative position.

Fig. 14 is a view similar to Fig. 13 with the parts in operative position.

Fig. 15 is a fragmentary side elevation of the upper end of the reversing lever.

Like reference characters refer to like parts throughout the drawings.

Referring particularly to Fig. 1, the machine comprises a base 1 upon which is slidably mounted a table or carriage 2 on guideways 3, Fig. 3. Bridges 4 and 5 at opposite ends of the base span the guideways 3 for the carriage, tool-heads 6 and 7 being mounted on the upper surfaces of the right and left hand bridges respectively, the tools in the construction shown being rotary boring tools. As shown in Figs. 2 and 3,

each bridge is arranged to support a plurality of toolheads, all the toolheads 6 on the right hand bridge being driven as a unit from a shaft 8, which carries a pulley 9, by a driving belt 10 which passes from said pulley 9 successively around the pulleys 11 on the toolhead spindles and idling pulleys 12 adjustably mounted in a horizontal slot 13 in the bridge. Similarly the spindles on the toolheads 7 on the left hand bridge are rotated in the same manner, by a belt 10' from a pulley 9' carried by a shaft 8', the belt passing around pulleys 11' on the toolheads and idling pulleys 12'. The two shafts 8 and 8' are each actuated from the main drive shaft 14 which is rotated from a source of power such as a motor 15 by a belt or chain drive to a pulley or sprocket 16 on the shaft 14, said drive shaft 14 being connected to the shafts 8 and 8' by clutch and brake units 17 and 18 respectively of usual construction. In this manner, the spindles in the toolheads on either bridge may be rotated independently of the movement of the spindles in the toolheads on the opposite bridge. Throughout the specification the toolheads on each bridge are referred to as a single toolhead, and the corresponding workpieces referred to as a single workpiece.

The clutch and brake units 17 and 18 are similar in construction and a description of one will suffice for both. Referring to Fig. 1, which shows the unit 17 in section, the shaft 8, which is journaled in a housing 17', has a slidable clutch member 18' slidable thereon and secured against rotation relative thereto by a key 19'. The clutch member 18' is provided with conical portions at opposite ends thereof and the right hand portion engages at its right hand end of movement with a conical brake member 20' forming a part of the housing 17', to hold the shaft 8 and accordingly the spindles in the tool heads 6 against rotation. The clutch member 18' when moved to the left out of engagement with the brake 20, engages a conical member 21' which is secured to the end of the shaft 14, above noted, so that when the member 18' is moved to the left hand end of its movement, said member 18' engages the member 21' to procure rotation of the shaft 8 in unison with the shaft 14. A circumferential groove 22' in the clutch member 18 is engaged by an actuating member 23' through which the clutch member 18' may be shifted.

The work to be operated upon is carried by a fixture or bracket 20 of any desired type mounted on the carriage, the fixture shown in Figs. 1, 2 and 3 being of the reversible or indexing type comprising a rotatable member 21 supported by trunnions 22. The rotatable member is adapted to clamp workpieces *a* indicated in dotted lines, in a position to be operated upon by the boring tools, by means of clamping bars 23 held in clamping position by wing nuts 24, the surface of the workpieces to be bored being located by a manually operated plug 25. Clamping bars 23 are provided on opposite sides of the rotatable member, so that the workpieces carried on the under side of the rotatable member may be operated upon by the tool while the finished workpieces on the upper side are being removed and unfinished workpieces substituted therefor. The rotatable member is swung through 180° after the workpieces on the under side, Fig. 1, have been completed to swing the unfinished workpieces beneath the trunnions into position to be operated upon by the boring tools on the opposite bridge

as the carriage moves in the opposite direction. In this manner, one group of workpieces may be loaded while the others are being bored, the rotatable member being held in desired position by an arm 21' which engages locating surfaces on opposite sides of the bracket as the member is swung through 180°.

The table or carriage is reciprocated on the ways by fluid under pressure, reciprocations of the carriage being procured by the admission of fluid under pressure alternately to opposite ends of a cylinder 26 supported by the base. Said cylinder has a piston 27 slidable therein, and a piston rod 28 extending outwardly thereof, the outer end of the piston rod being connected to a depending bracket 30 on the carriage. The movements of the carriage are controlled by spaced reversing dogs 31 and 32 which are mounted on the carriage which alternately engage and actuate a reversing lever 33, thereby to direct the fluid under pressure alternately to opposite ends of the cylinder and cause the carriage to reciprocate. The lower end of the reversing lever engages a pin 34, Fig. 4, carried by a crank 35, the latter being mounted on the forward end of a pilot valve 36, so that rocking movement of the reversing lever, in response to engagement of said lever with the dogs 31 and 32 rocks said valve member, thereby controlling the direction of flow of fluid to the cylinder.

The hydraulic system for actuating the carriage is shown most clearly in Figs. 4, 7 and 12. Fluid under pressure is admitted through a pipe 37 from any suitable source such as a fluid pressure pump to a channel 38 in the rearward end of a throttle valve 40 rotatably mounted in a longitudinal bore 41 in the casting 42 in which the valve mechanisms are mounted. The throttle valve is recessed at 43 to intersect the channel 38 so that the amount of fluid flowing from the recess into a port 44 provided in the bore 41 adjacent the valve recess may be varied in response to turning movement of the valve 40 as will be apparent from Fig. 7. The port 44 is connected by a channel 45 (pipe 45', Fig. 12) in the casting 42 to a central inlet port 46 in the casing or sleeve 47 for the reversing or main valve 48, said casing being received in a transverse bore 50 in the casting 42. The casing 47 is provided with spaced outlet ports 51 and 52 adjacent opposite ends thereof, and in line with the inlet port 46, and exhaust ports 53 and 54 intermediate the inlet port 46 and the ports 51 and 52 respectively, said exhaust ports being connected by a channel 55, Fig. 5, to an exhaust outlet 56. The two outlet ports 51 and 52 are connected respectively to longitudinal channels 57 and 58 in the casting 42, which channels provide connections through speed reducing or slow-down valves 60 and 61 and pipes 62 and 63 to opposite ends of the cylinder 26. The channels 57 and 58 are represented as separate elements in Fig. 12 in order to make the arrangement of the parts more clear, said channels being identified in Fig. 12 as 57' and 58'. Although the ports 51 and 52 open directly into the channels 57 and 58 as shown in Fig. 7, said channels are represented in the diagrammatic showing of Fig. 12, as being connected by pipes 57'' and 58'' respectfully to said ports 51 and 52. Channel 45 is indicated in Fig. 12 by a pipe which, to avoid confusion, is identified as 45'.

The main valve 48 comprises spaced cylindrical portions 64, 65, 66 and 67 connected by corresponding cylindrical portions 68, 70 and 71 of smaller diameter and end portions 72 and 73 also

of smaller diameter, said end portions 72 and 73 having slightly enlarged ends 74 and 75. The main valve has a central opening 76 longitudinally therethrough, the ends of which are substantially closed by plugs 77 and 78, the latter having small channels or bleed ports 80 and 81 respectively therethrough. Ports 82, 83 and 84 are provided in the right hand end cylindrical portion 72, the central cylindrical portion 70 and the left hand end cylindrical portion 73, respectively, to permit fluid under pressure to enter and escape from the central opening 76 so that fluid may flow from the inlet port 46 into the central opening 76 through port 83 and out through either of the bleed ports 80 or 81 in the plugs 77 or 78 or out the ports 82 and 84, as will hereinafter appear. Caps 85 and 86 are arranged to cover the ends of the bore 50 to retain the casting 47 therein, said caps having bores 87 and 88 respectively therein, which are of a suitable diameter slidably to receive the enlarged ends 74 and 75 of the main valve 48. Channels 90 and 91 in the caps connect the bores 87 and 88 to channels 92 and 93 in the casting 42, and the latter channels 92 and 93 intersect the longitudinal bore 94 in the casting 42 in which the pilot valve 36 is mounted. The channels 92 and 93 are represented by pipes 92' and 93' in Fig. 12, the channels 90 and 91 being shown in this figure as integral with casting 42.

The pilot valve is arranged to provide fluid connection alternately from said channels 92 and 93 to the exhaust opening 56. As best shown in Figs. 4 and 7, the pilot valve 36 is provided with a longitudinal channel 96 throughout a portion of its length, said channel opening at the rearward end of the valve into the bore 94 which receives said valve, said bore being connected by a channel 95, indicated by an open pipe 95 in Fig. 40 12, in casting 42 to the exhaust 56. The valve is also provided with a semicircular recess 97 intersecting the longitudinal channel, said recess being located adjacent the intersection of channels 92 and 93 with the bore 94. From a consideration of Fig. 7, it will be apparent that movement of the pilot valve 36 in response to rocking movement of the reversing lever 33, as above pointed out, alternately connects one of the channels 92 and 93 to the exhaust opening 56 at the same time closing the opposite channel.

Fluid entering through the inlet port 46 passes into the central opening 76, Fig. 7, of the main valve and out through the small channels 80 and 81 in the plugs into channels 90 and 91. Since one of the channels 92 or 93 is closed to the exhaust, fluid pressure is built up in the channel and bore at the closed end, thereby urging the main valve 48 into its opposite end position, the fluid escaping from the bore in the other cap through the pilot valve and out the exhaust opening to permit movement of the main valve. Similarly, when the pilot valve is reversed, the main valve is urged in the opposite direction.

With the pilot and main valves in the position shown in Figs. 7 and 12, fluid from the pump flows through the throttle valve 40, and the channel 45 to the inlet port 46 in the casing 47, from which port the fluid passes through the port 83 into the opening 76 within the main valve passing through the port 84 into the port 52 and thence to the channel 58. The movement of the fluid under pressure in the casing 47 is limited by the cylindrical portions 64, 65, 66, 67, which retain the fluid outside the main valve between the adjacent cylindrical portions. From the

channel 58 the fluid enters the left hand end of the cylinder 26 through the pipe 63, thereby urging the piston 27 and accordingly the carriage to the right. Fluid from the central opening 76 in the main valve also passes through the bleed port 81, building up pressure in the channel 91 and bore 88, thereby maintaining the valve in the right hand position shown. As the carriage reaches the right hand end of its stroke, the reversing dog 32 engages and rocks the reversing lever, thereby rotating the pilot valve counterclockwise to permit fluid to exhaust through the channel 93 from the bore 88 at the left hand end of the main valve and to close the channel 92 connecting to the right hand end of the main valve, whereby pressure is built up on the right hand end of the main valve, urging said valve to the left. This movement of the main valve cuts off the flow of fluid under pressure from the inlet port 46 to port 52 and provides fluid connection between the inlet port 46 and the port 51 to the channel 57 connecting said port to the pipe 62, and thence to the right hand end of the cylinder 26 so that the direction of movement of the carriage is reversed, the carriage being urged to the left until the reversing dog 31 engages and rocks the reversing lever at left hand end of stroke, thereby returning the pilot valve 36 to the original position, so that the movement of the carriage is again reversed and the carriage is urged to the right.

As the fluid under pressure is admitted to the left hand end of the cylinder 26, the main valve being in the position shown, fluid is exhausted from the right hand end of said cylinder through the channel 57 and the port 51 into the space between the spaced cylindrical portions 64 and 65, through the exhaust port 53 into the channel 55 and thence to the exhaust opening 56. When the main valve 48 is shifted to the left to cause the 40 table to move toward the left, fluid exhausting from the left hand end of the cylinder flows from the channel 58 through the port 52 into the space between the cylindrical portions 66 and 67, through the exhaust port 54 into the channel 55 45 and out through the exhaust opening 56.

The table is actuated at maximum speed during the inoperative movement of said table when the boring tools are out of engagement with the workpieces, said table being slowed down during 50 the operative boring movement when the tool on either bridge is in engagement with the workpiece. As shown in Figs. 1 and 6, speed control dogs 98 and 99 are mounted on the under side of the carriage for engagement with upstanding latches 100 and 101. Arms 102 and 103, Fig. 6, are rigidly mounted on shafts 104 and 105 respectively, the latter being rotatably mounted in the base 1, and support the latches at the ends remote from the shafts 104 and 105. The latches 100 and 101 are pivotally mounted on pins 106 and 107 in the end of the arms, said latches being held positively against movement from upstanding position in one direction by engagement of a surface of each latch with a portion of the corresponding arm. The rocking movement of the latches in the opposite direction is limited in extent, by plungers 108 and 109 mounted in recesses 110 and 111 respectively, in the arms 102 and 103, said plungers being held in engagement 65 with the latches by springs 112 and 113 thereby resiliently holding the latches in upstanding position for engagement with the speed control dogs. The shafts 104 and 105 support, in addition to the arms 102 and 103, other arms 114

and 115, the latter arms being similarly rigidly mounted on said shafts, and the outer end of said arms 114 and 115 engaging the upstanding ends 116 and 117 of the speed control valves 60 and 61.

As the carriage is actuated to the left by fluid passing valve 60 to the right hand end of cylinder 26, the speed control dog 98 engages the upper end of the latch 100 urging the latch downwardly, thereby rotating the arm 102 and accordingly the arm 114 counterclockwise and urging the upstanding end 116 of the speed reducing valve 60 downwardly to diminish the fluid flow to the cylinder 26, thereby reducing the rate of movement of the table during the movement of the workpiece past the tool on the left hand bridge. The dog 98 is located to engage the latch 100 immediately prior to engagement of the tool with the workpiece and the upper end of the latch and the corners of the dog are bevelled to permit said dog to ride over the end of the latch in order to actuate said latch. The dog 98 is somewhat longer than the length of the workpiece to be operated upon so that the latch 100 is depressed just prior to the engagement of the boring tool with the workpiece and is released directly as the boring tool passes beyond the workpiece. It is not necessary that the slow-down valve be released prior to reversal of the carriage movement since the carriage is positively actuated by fluid under pressure until the pilot valve 36 has been shifted from one extreme position to the other.

It will be noted that the table is slowed by the latch 100 in only one direction of table travel, that is, as the table is reversed after the tool has passed over the workpiece, the latch 100, which is depressed during the boring operation and is released at the end of the stroke, is rotated against the pressure of the spring 112 so that as the carriage moves to the right, the arm 102 is not rotated and accordingly the speed reducing valve is not depressed. Similarly, as the carriage continues to move to the right, the dog 99 depresses the latch 101, rotating the arm 103 and 115 clockwise and depressing the upstanding end 117 of the speed reducing valve 61 to diminish the rate of travel of the table as the workpiece passes the boring tool on the right hand bridge. The dog 99, similar to the dog 98, reduces the speed of the carriage during the right hand movement only thereof, the latch 101 rocking against the pressure of the spring 113 as the carriage subsequently moves to the left after having been reversed so that the speed reducing valve 61 is not depressed during the left hand movement of the carriage.

The speed reducing or slow-down valves 60 and 61 actuated by the dogs 98 and 99 are located in the forward ends of the channels 57 and 58, substantially vertical bores being provided in the casting 42 for the reception of said valves, the valve 60 being shown in Fig. 4 and the valve 61 being shown in Fig. 11. Since the valves are identical in construction, the description of one will suffice for both. Referring particularly to Fig. 11, which shows the speed control valve 61 for the left hand end of the cylinder 26, the valve 61 is slidably received in the vertical bore 118 in the casting 42, the lower end of the bore intersecting the forward end of the channel 58. A similar bore 119, Fig. 4, which intersects channel 57, receives the valve 60 for the fluid passing to the right hand end of the cylinder 26. A cap 120 is provided for the upper end of the bore 118 beyond which the upstanding end 117 of the valve stem 121 extends and the lower end of the

valve stem is enlarged at 122 for engagement with the under surface of the cap to limit the upward movement of said stem and to hold the end 117 in position for engagement with the arm 115. A pin 123 extends through the lower end of the valve stem 121 and engages in openings 124 in the valve, the openings being a larger diameter than the pin to permit movement of the stem relative to the valve, whereby the movement of the valve stem in response to the rocking of arm 115 may be greater than the resultant valve movement. Directly beneath the enlarged portion 122 is a flange 125, the under side of which is engaged by a coil spring 126 surrounding the stem. The lower end of the spring engaging in a recess 127 formed in the upper end of the valve, said spring 126 normally holding the pin 123 against the upper edge of the openings.

The valve is provided substantially centrally thereof with a transverse bore 128, one end of which receives the inner end of an elongated rod 130, which is tapered at 131, in order to regulate and to limit the movement of the valve within the bore. The lower end of the valve is reduced in diameter as indicated at 132 to engage within the bore 133 of a sleeve 134 received within the lower end of the bore 118, said sleeve having a port 135 in the side coinciding with the opening to the channel 58, and the top surface of the casing being substantially plane. A transverse groove or notch 136 is formed in the lower end of the valve 61, which, when the valve is in the normal position shown in Fig. 11, is open to the fullest extent, the bottom of the valve coinciding with the upper edge of the sleeve. A coil spring 137 which encircles the reduced portion of the valve normally maintains the valve in this position, said spring engaging the upper surface of said sleeve and the shoulder 138 on said valve at lower and upper ends respectively. The spring 137 is lighter than the spring 126 so that as the valve stem 121 is urged downwardly, the valve 61 moves downwardly therewith, the spring 137 being compressed until the upper edge of the transverse bore 128 engages the inner end of rod 130 after which said valve is held by said rod against further downward movement during the continued downward movement of said valve stem, the pin 123 which connects said valve to said valve stem moving relative to the openings 124 by compression of spring 126. A central channel 140 is formed longitudinally through the valve in order to permit fluid to pass to and from the upper end of the bore 118 in order to permit unrestricted movement of the valve. As the valve stem 121 is urged downwardly in response to the speed control dog 99, the valve 61 being urged downwardly therewith, the groove 136 is partially closed, to limit the amount of fluid flowing from the channel 58 into the port 135 which connects to the pipe 63, thereby reducing the speed of the table. The flow of fluid through the slow-down valve is obviously reduced in proportion to the amount of downward movement of said valve and the speed reduction is accordingly controlled by the position of the lower edges of the space controlled dogs 98 and 99.

The speed reducing valve 60 is similarly constructed and mounted in the vertical bore 119, the lower end of said bore intersecting the forward end of the channel 57 and the outlet for said valve 60 being indicated at 62 in Fig. 4. The sliding movement of valve 60 is controlled by a rod 141, Fig. 4, similar to rod 130, having a tapered end corresponding to the tapered end of said rod.

130, said end engaging in the transverse bore 142 of valve 60. The forward end of the rods 130 and 141 are threaded as indicated at 143, Fig. 4, on the rod 141, rotation of the rods procuring in or out movement in the casting 42 to limit the movement of said valves and accordingly the extent to which the grooves on said valves are closed. The cover plate 144 on the front of the casting 42 is recessed as indicated at 145 to receive a coil spring 146 which surrounds the rod 141, the forward end of said coil spring engaging the inner surface of a knob 147 by which said rod is rotated, another recess 148 being provided in the front of the casting to receive a small portion of the knob 147. The cover plate 144 is similarly recessed and provided with a spring which is urged against the inner surface of a knob 149 for the rod 130, the knobs being indicated on the front of the machine in Fig. 1.

20 The rotation of the boring heads on the bridges is controlled by valves 150 and 151 which are received in longitudinal bores 152 and 153 in the casting 42 directly beneath and parallel to the channels 57 and 58. As best shown in Fig. 8, 25 the valves are provided respectively with longitudinal channels 154 and 155 extending from the inner or rearward end of the valves, said channels being closed at their inner ends by plugs 156 and 157. Transverse horizontal channels 158 and 160 in the valve 150 and similar transverse horizontal channels 161 and 162 in the valve 151 intersect the longitudinal channels 154 and 155 respectively adjacent their forward ends; and vertical channels 163 and 164, extending downwardly through the valves, also intersect the longitudinal channels 154 and 155 respectively adjacent their forward ends, said vertical channels 163 and 164 being indicated as horizontal channels identified as 163' and 164' respectively 30 in Fig. 12 for the sake of clarity. Other transverse channels 165, 166 and 167 intersect the longitudinal channel 154 and similar transverse channels 168, 170 and 171 intersect the channel 155 adjacent the rearward ends thereof. Channels 167 and 171 extend completely through the valve and intersect with downwardly opening channels 172 and 173 respectively. Short longitudinal channels 174 and 175, having downwardly extending vertical channels 176 and 177 intersecting therewith, are open into the bores 152 and 153 beyond the rearward end of the valves. Vertical channels 178 and 180 extend completely through the valves 150 and 151 substantially midway between the downwardly extending channels 172 and 176 in valve 150 and 173 and 177 in valve 151 respectively. The valves are held against rotation by longitudinal recesses 181 and 182 which are engaged by pins 183 and 184 extending transversely in the casting 42, said pins being 40 held in engagement with the recess by springs 185 and 186, the latter held in place by plugs 187 and 188 mounted in the casting. The valves are arranged for movement into three different positions depending upon the operation of the 45 boring heads. With the valves in the position shown, which is the midway position, the pins are in engagement with notches 190 and 191 in the recesses 181 and 182, said detents locating the valve readily in mid position. In the automatic or mid position the boring tools on opposite heads are rotated during the operative stroke of the carriage, that is, the right hand boring head is rotated during the right hand movement of the carriage and the left hand boring head is rotated during the left hand move-

5 ment of the table. In order to stop the rotation of the boring heads, the valves 150 and 151 are pushed rearwardly until the inner surface of knobs 192 and 193 on the forward ends of said valves engage the surface of the cover plate member 144, as will be apparent in Fig. 8. If it is desired to rotate the boring heads continuously, the valves may be drawn forwardly until shoulders 194 and 195 on the valves 150 and 151 engage the inner surface of the said plate 144 at which time the clutch and brake mechanisms controlled by said valves operate entirely independently of the reciprocations of the table.

10 When the valves 150 and 151 are in the central position shown, the boring heads are started 15 and stopped in response to the reversal of the table movements at either end, the left hand boring head being started at the right hand end of movement of the table and being stopped at the left hand end of movement directly after 20 the workpiece has passed the boring tool during the left hand movement, and similarly the right hand boring head being started at the left hand end of movement of the table and stopped at the right hand end of movement of the table directly 25 after the workpiece has passed boring tool on the right and bridge. The starting and stopping of the boring heads are controlled by pistons 196 and 197 slidably mounted in transverse bores 198 and 199 in casings 200 and 201 mounted on opposite sides of the casting 42, transverse bores 202 and 203 being provided in said casting, as shown in Fig. 7, for the reception of said casings. The pistons are provided with elongated piston rods 204 and 205 extending beyond said casings, and 30 said piston rods are positively connected respectively to the clutch and brake mechanisms 17 and 18 by engagement of said piston rods with the actuating members 23' of the clutch and brake units 17 and 18 respectively. The arrangement is such that the clutches are disengaged 35 and the brakes engaged when the pistons 196 and 197 are in extreme right and left hand positions, respectively.

40 Referring particularly to Fig. 7, fluid connections are provided between the inner ends of the bores 198 and 199 which receive the pistons 196 and 197 and the corresponding channels 57 and 58 respectively, through vertical channels 206 and 207 formed in the casting 42 and intersecting 45 channels 57 and 58, through the vertical channels 178 and 180 in the valves 150 and 151 and short channels 208 and 209 in line with the channels 206 and 207, the channels 208 and 209 opening into the inner ends of bores 198 and 199. 50 The channels 206, 207, 208 and 209 are indicated by pipes 206', 207', 208', and 209' respectively in Fig. 12.

55 Fluid connection is provided from the outer ends of the bores 198 and 199 for the pistons 196 and 197 to the opposite channels 58 and 57 respectively through channels 214 and 215 in the casings 200 and 201, the channels 216 and 217 in the casting 42 in line with said channels 214 and 215, into the transverse channels 166 and 170 respectively in the valves 150 and 151, into which the channels 214 and 215 open, and thence to the longitudinal channels 154 and 155. The channels 214 and 216 are indicated in Fig. 12 by a pipe 218, and the channels 215 and 217 are indicated by a pipe 220. Referring to Fig. 10, fluid connection is provided from the longitudinal channel 154 in the valve 150 to the left hand channel 58 to complete the connection from the outer end of the casing for the right hand piston 60 65 70 75

- to the left hand channel 58. A transverse bore or channel 221 is provided in the casting 42 midway between the channels 57 and 58 and the bores 152 and 153 for the valves 150 and 151.
- 5 A vertical channel 222 extending from the channel 58 intersects the channel 221, and another vertical channel 223, which intersects the channel 221 enters into the bore 152 which receives valve 150 and connects with the vertical channel 163 in said valve. Since the channel 163 intersects the longitudinal channel 154, fluid connection is thus provided from channel 58 through valve 150 to the outer end of casing 200.
- 10 Similarly, the longitudinal channel in the valve 155 is connected to the channel 57 in the casing. Referring to Fig. 9, the casting 42 is provided with a transverse bore or channel 224 parallel to the channel 221, an intersecting vertical channel 225, the upper end of which opens into the channel 57 and the lower end of which intersects the channel 224, and a vertical channel 226, the latter intersecting the channel 224 and opening into the bore for the valve 155 at a point which coincides with the vertical channel 164 in said valve, said vertical channel 164 intersecting the longitudinal channel 155 of the valve 150. Thus fluid connection is provided from the outer or left hand end of casing 201 through channel 155 to the channel 57. Fluid flows through channels 222, 221, and 223 in that order, and said channels are indicated in Fig. 12 by the single pipe 227 between channel 58 and valve 150. Similarly the channels 225, 224 and 226, in that order are indicated in Fig. 12 by a pipe 228 between channel 57 and valve 151.

It will thus be seen that with the main valve 48 in the position shown in Figs. 7 and 12, so that fluid under pressure is admitted to the channel 58, the channel 57 being connected through said valve to the exhaust outlet 56, fluid under pressure passes from the channel 58 through the pipes 207' and 209' into the inner end of the casing 201 urging the piston 197 to the left, thereby disengaging the clutch and energizing the brake in the left hand clutch and brake unit 18, the fluid from the right hand end of the casing 201 exhausting through the pipe 220 into the longitudinal channel 155 and through the pipe 228 to the channel 57 which is connected to the exhaust, as above pointed out. At the same time fluid under pressure from the channel 58 passes through the connection 227 into the longitudinal channel 154 and through the pipe 218 to the outer or right hand end of the casing 200, thereby urging the piston 196 to the left, bringing the clutch into engagement and releasing the brake in the clutch and brake unit 17. The fluid from the left hand or inner end of the casing 200 exhausts through the pipes 212 and 210 through channel 178 into the channel 57 which is connected to the exhaust. It will be apparent that, as the movement of the carriage is reversed at the left hand end of the stroke, the boring tools on the left hand bridge are brought to rest and the boring tools on the right hand bridge are set in rotation so that, as the carriage moves toward the left, the completed work-piece is drawn past the boring tools on the left hand bridge while the said boring tools are not in motion, the right hand boring tools rotating in readiness to operate on the unfinished work-piece as the carriage continues to move to the right.

Similarly at the right hand end of the carriage movement, when the main valve is urged

into the left hand position, thereby admitting fluid under pressure to the channel 57 and connecting the channel 58 through said valve to the exhaust outlet 56, the pistons 196 and 197 are both urged from the position shown in Fig. 12 to the right, thereby stopping the rotation of the tools on the right hand bridge and setting the tools in the left hand bridge in motion. The piston 196 is moved to the right by fluid under pressure which flows from the channel 57 through the pipes 206' and 208' into the left hand end of the casing 200, fluid from the right hand end of the casing exhausting through connections 218, longitudinal channel 154 and the pipe 227 to the channel 58, which is now connected to the exhaust. The piston 197 is urged to the right by fluid under pressure from the channel 57 through the pipe 228, the longitudinal channel 155 and the pipe 220 into the left hand end of the casing 202, fluid from the right hand end exhausting through the pipes 209' and 207' into the channel 56 which is now connected to the exhaust.

In order to stop the rotation of the boring heads on either bridge, the corresponding valve 150 or 151 is pushed inwardly until the inner surface of knob 192 or 193 on the forward ends of the valves engages the surfaces of the plate member 144. With the valves in this inward position fluid under pressure is admitted to both ends of the casings 200 and 201 regardless of the position of the carriage. By reason of the difference in area of the inner and outer ends of the pistons 196 and 197, the piston rods being located on the outer ends of said pistons, the said pistons are urged into right and left hand ends of the casings 200 and 201 respectively in which position the clutches of both units 17 and 18 are disengaged and the brakes of said units are energized. Referring particularly to Figs. 8, 10, and 12, the throttle valve 40 is provided with a longitudinal channel 230 therein extending forwardly from the recess 38, the forward end of the channel intersecting a transverse channel 231, the latter extending outwardly to a circumferential groove 232 in the valve 40. A horizontal channel 233, represented by a pipe 233' in Fig. 12, is provided in the casting and extends from the bore 41 adjacent the groove 232 to the bore 152, the opening of said channel into the bore 152 being closed when the valve is in automatic or central position, but with the valve in inward position said opening coincides with the short transverse channel 158, thereby admitting fluid under pressure from the fluid inlet 37 into the longitudinal channel 154 and outwardly through the short transverse channel 167 which in inward position coincides with the opening to the connection 218 to the casing 200. A corresponding channel 234 represented by a pipe 234' in Fig. 12, is provided in the casting 42 extending from the bore 41 adjacent the groove in the valve 41 to the bore 153 for the valve 151, the opening in the bore being closed when the valve is in central position, but when the valve is in inward position, said opening coincides with the transverse channel 161 which intersects the longitudinal channel 155, thereby admitting fluid under pressure from the fluid inlet 37 through the longitudinal channel 155 to the pipe 228, the transverse channel 171 in the valve 151 coinciding with the opening to said connection from the valve, the fluid flowing through said connection to the left hand end of the casing 201. Fluid under pressure is admitted to the inner end of the casing 200 from the longitudinal chan-

nel 154 through the channel 167 to the vertical channel 172, which in the inward position of the valve coincides with the opening to the pipe 208' to the casing 200. In a similar manner, fluid under pressure enters the inner or right hand end of the casing 201 from the channel 155 through the channel 171 and the vertical channel 173 into the pipe 209' which connects to said casing. It will thus be seen that, with the valves 150 and 151 in inward position, fluid under pressure is admitted to both ends of casings 200 and 201, so that the pistons 197 and 198 are urged to extreme right and left hand positions respectively, thereby stopping the rotation of the boring heads independently of the movement of the carriage, said heads remaining stopped until the valves 150 and 151 are again moved.

When the valves 150 and 151 are in extreme forward or outer position, the boring heads on both bridges rotate continuously independently of the movement of the carriage.

Referring again to Figs. 8 and 12, fluid under pressure from the fluid inlet 37 flows through channels 230 and 231 into the channel 160 of valve 150, since with valve 150 in forward position, channel 160 coincides with the opening to the channel 233, the fluid flowing from said channel 160 through the longitudinal channel 154 and the transverse channel 165 into the pipe 218 to the right hand end of the casing 200, the channel 165 now coinciding with the opening to the pipe 218. At the same time, fluid from the left hand end of casing 200 exhausts through the pipe 208' into the downwardly extending channel 176, which coincides with the opening to said pipe, into the longitudinal channel 174 and thence to the bore 152 for the valve 150 at the rearward end of the valve. An exhaust connection 235, Fig. 8, is provided at the rear end of the bore 152 through which the fluid may exhaust from the channel 174, whereby fluid from the left hand end of the casing 200 may exhaust. Similarly, with the valve 151 in forward position, fluid under pressure flows from the fluid inlet 37 through the channel 234 into the transverse bore 162, which now coincides with the opening of the channel 234, and thence into the longitudinal channel 155 and through the transverse channel 168 to the left hand end of the casing 201 through the pipe 220, said channel 168 now coinciding with the opening to pipe 220. Fluid from the right hand end of the casing 201 exhausts through the pipe 209' into the vertical channel 177, through the longitudinal channel 175 and into the bore 153 of the valve 151 at the rearward end of the valve. An exhaust connection 236, Fig. 8, is provided in the rearward end of the bore 153 for the exhaust fluid from the channel 175, so that fluid from the right hand end of the casing 201 may exhaust. It will thus be seen that with the valves 150 and 151 in forward position, the pistons are urged into left and right hand positions respectively in which positions both of the clutch units 17 and 18 are engaged and the brakes of the same units are disengaged so that the boring heads on both ends of the machine rotate continuously regardless of the reciprocating movements of the carriage.

It will be noted that either valve 150 or 151 may be placed in any of its three positions independently of the position of the other valve. That is, either valve may be placed in the inward position in which the boring head for the corresponding bridge does not rotate, in auto-

matic position in which the boring head for the corresponding bridge rotates in response to movements of the carriage, or in forward position in which the boring head for the corresponding bridge rotates continuously, regardless of the position of the other valve.

The carriage may be positively brought to rest in any desired position of travel to stop the operation of the machine, the mechanism by which the table is brought to rest being under the control of the operator. Referring to Fig. 1, stop dogs 237 and 238 are adjustably mounted on the under side of the carriage and are adapted at extreme left or right hand movements of the carriage to engage respectively with studs 240 and 241 rigidly mounted on the base of the machine. The upper end of the reversing lever 33, which is engaged by the reversing lugs 31 and 32, is provided with an eccentrically mounted striking member 242, said member being mounted on the rearward end of a horizontal shaft 243 pivotally mounted in the upper end of the reversing lever, the forward end of the shaft carrying an upstanding lever 244 secured against rotation on said shaft. Rocking movement of the lever 244 swings the striking member 242, thereby moving the striking surface of said member toward or away from the reversing dogs. A spring 245 is mounted in a recess 246 surrounding the shaft 243, said spring engaging a portion of the upper end of the lever 244 to hold the lever and thus the striking member in desired position.

Figs. 13 and 14 are fragmentary views of the mechanism for stopping the movement of the carriage, Fig. 13 showing the reversing dog 31 and the stop dog 237 at the right hand end of the carriage and the relative position of said dogs to the reversing lever when the carriage is in substantially mid position, and Fig. 14 showing the same dogs when the carriage has been brought to a stop at the end of the left hand movement. When the lever 244 is rotated from the vertical position of Fig. 13 to the diagonal position shown in Fig. 14, the surface of the striking member is moved a substantial distance away from the reversing dog 31 so that as the carriage moves toward the left, the reversing dog engages the striking member and swings the reversing lever into vertical position at which time the stud 240 engages the left hand edge of the stop dog 237 so that the reversing lever is actuated only into vertical position and thus rotates the reversing valve to close both channels 92 and 93, thereby to prevent movement of the table in either direction. The fluid pressure, acting on the right hand end of the piston which actuates the table, serves to hold the stop dog in engagement with the stud. When the operator wishes to set the machine again in operation, the lever 244 is rotated into a vertical position so that the surface of the striking member is moved to the right with the result that the upper end of the reversing lever is swung to the left, the reversing dog being in engagement with the striking surface, so that the channel 85 is again open to the exhaust and the table moves to the right. In a similar manner when the lever 244 is swung into a diagonal position to the right of the vertical position, the carriage is brought to rest at the right hand end of movement by the engagement of the stop dog 238 with the stud 241 just as the reversing dog 32 engages the striking surface and moves the reversing lever into vertical position. Subsequent return of the lever to vertical position causes the

reversing lever to swing to the right rotating the pilot valve to permit fluid to exhaust through the channel 85, thereby causing movement of the carriage to the left.

- 5 When the carriage is normally reciprocated and the lever 244 is in vertical position, each of the reversing dogs engages the reversing lever and carries said lever beyond the vertical position, before the carriage is brought to rest by engagement of the corresponding stop dog with the corresponding stud on the base, so that the carriage is reversed by said reversing dog and travels in the opposite direction. However, when the carriage is to be brought to rest, the operator swings the lever 244, thereby spacing the striking member from the reversing dog so that as the reversing dog engages and actuates the reversing lever, the corresponding stop dog engages the corresponding stud and prevents the carriage from traveling far enough to swing said reversing lever beyond the vertical position. It will be noted that the machine may be brought to rest in any desired position by suitable adjustment of the stop dogs relative to the studs so that if the boring head on only one bridge is to be used, the carriage may be brought to rest after the workpiece has been withdrawn from engagement with the operative boring head without bringing the workpiece into operative engagement with the inoperative boring head on the other bridge. The speed reducing dogs are preferably adjusted so that when the stud engages the stop dog to bring the carriage to rest, said carriage will be moving at a reduced speed, thereby preventing excessive shock on the machine. With the parts in the position shown, when the carriage is brought to rest at either end of the stroke, the location of the speed reducing valve is such that the table is traveling at reduced speed.

By the valve construction shown the carriage has a short dwell at each end of the stroke before the beginning of the movement of the carriage in the opposite direction. As soon as the reversing lever is shifted by either of the reversing dogs, the corresponding stop dog engages the cooperating stud on the base and prevents further movement of the carriage until the main valve 48 is shifted. It will be apparent that when the pilot valve 36 is shifted, as a result of the shifting movement of the reversing lever, the flow of fluid through either of the conduits 92' or 93', Fig. 12, is cut off, but the main valve 48 is not shifted until the pressure at the end of the valve has been built up by passage of fluid through the bleed port 86 or 87 to a sufficient extent to shift the valve. Obviously the length of time occupied by the dwell of the carriage is controlled by the size of the bleed ports and the dwell occurs subsequent to the shifting of the pilot valve 36 and between the shifting of this valve and the shifting of the main valve 48.

Since the forward end of the throttle valve 40 is provided with a crank 247, Fig. 4, by which said valve may be opened or closed as desired, the hydraulic system is completely controlled from the front of the machine. Movement of crank 247 either manually or in response to the reversing dogs rotates the pilot valve to direct fluid alternately to opposite ends of the cylinder which actuates the carriage, and movement of crank 247 varies the maximum speed of the carriage by opening or closing the throttle valve 40. The reduction in speed, which is controlled by the speed reducing valves, is determined by ad-

justment of knobs 147 and 149; thereby controlling the movement of said valves in response to movement of the carriage. The movements of the boring heads are also controlled from the front of the machine by knobs 192 and 193, said heads either rotating continuously, or being actuated in response to movement of the carriage, or remaining at rest independently of the carriage movement, depending on whether the valves are in full outward position, central or 10 mid position, or full inward position.

I claim:

1. In a machine of the class described, a tool member and a work-supporting member, a reciprocating carriage supporting one of said members to procure a relative movement between said members, means to actuate said carriage comprising a fluid pressure source, a cylinder and piston, one of which is connected to said carriage, and reversing means alternately to admit fluid under pressure from said source to opposite ends of the cylinder, and means to control the operation of said tool member, said means comprising a piston and a cylinder, and valve means normally admitting fluid under pressure alternately to opposite ends of said cylinder in response to said reversing means, said valve means being arranged for manual movement to procure continuous operation of said tool independently of said reversing member, and for other manual movement to maintain said tool member at rest independently of said reversing means.

2. In a machine of the class described, a rotary tool member, a carriage actuated by fluid under pressure and arranged for reciprocatory movement, means to control the rotation of said tool member comprising a piston and cylinder, said piston when adjacent one end of said cylinder procuring rotation of said tool member and when adjacent the other end of said cylinder maintaining said tool member at rest, means alternately to direct fluid under pressure to opposite ends of said cylinder in response to movement of said carriage whereby said tool rotates during the movement of the carriage in one direction and remains at rest during the movement of the carriage in the opposite direction, and manually controlled means to admit fluid under pressure independently of the carriage movement to said cylinder whereby the tool member remains at rest, said manually controlled means being further operable to admit fluid to the opposite end of said cylinder whereby the tool member rotates continuously independently of the carriage movement.

3. In a machine of the class described, a base, a reciprocating table on said base, rotary spindles on said base at opposite ends of said table, means to actuate said table, comprising a pressure source, a cylinder and piston, one of which is connected to said table, and reversing means alternately to admit fluid under pressure from said source to opposite ends of the cylinder through connections between said reversing means and said cylinder, a throttle valve in each of said connections and means 24 said table for actuating one of said throttle valves in one direction only of the movement of the table to diminish the rate of travel during a portion of the movement of the table in the one direction and other means on said table to actuate the other throttle valve in response to movement of said table in the opposite direction to diminish

the rate of travel during a portion of the table movement in said opposite direction.

4. In a machine of the class described, a base having a reciprocating carriage mounted thereon, rotary tool members mounted on said base adjacent opposite ends of said reciprocating carriage, means to rotate the tool members adjacent one end of said base, and separate means to rotate the tool members at the opposite end of the base, fluid pressure means to actuate said carriage, means to control the rotation of said tool members in response to movement of said carriage, whereby the tool members on one end of said base are started and stopped at opposite ends of the carriage movement, and the tool members on the opposite end of the base are stopped and started at opposite ends of the carriage movement with the tool members at either end of the carriage rotating only when the carriage is moving toward said tool members, and individual valve means to control the rotation of the tool members on opposite ends of the base, said valve means being arranged for manual movement to procure continuous operation of the tool members on either end of the base independently of said reciprocating carriage, and for other manual movement to maintain said tool members at rest independently of said reciprocating carriage.

5. In a machine of the class described, a tool member and a work-supporting member, a carriage on which one of said members is mounted, fluid pressure actuated means to procure reciprocation of said carriage for a relative movement between said members, reversing means including a reversing valve for controlling the admission and exhaust of fluid under pressure to and from said fluid pressure actuated means for reversing the carriage movement, a rotary spindle on which one of said members is mounted, other fluid pressure actuated means for controlling the rotation of said spindle, the admission and exhaust of fluid under pressure to and from said last means being controlled by the above-mentioned reversing valve for procuring cessation of rotation of the spindle at one end of the carriage movement, and other valve means for controlling the admission and exhaust of fluid under pressure to said last fluid pressure actuated means for rendering said means inoperative, whereby the spindle member will rotate continuously independently of the carriage movement.

6. In a machine of the class described, a tool member and a work-supporting member, a carriage on which one of said members is mounted, fluid pressure actuated means to procure reciprocation of said carriage for a relative movement between said members, reversing means including a reversing valve for controlling the admission and exhaust of fluid under pressure to and from said fluid pressure actuated means for reversing the carriage movement, a rotary spindle on which one of said members is mounted, other fluid pressure actuated means for controlling the rotation of said spindle, the admission and exhaust of fluid under pressure to and from said last means being controlled by the above-mentioned reversing valve for procuring cessation of rotation of the spindle at one end of the carriage movement, and other valve means for controlling the admission and exhaust of fluid under pressure to said last fluid pressure actuated means for rendering said means inoperative, whereby said spindle will remain at rest independently of the carriage movements.

7. In a machine of the class described, a tool member and a work-supporting member, a carriage on which one of said members is mounted, fluid pressure actuated means to procure reciprocation of said carriage for a relative movement between said members, reversing means including a reversing valve for controlling the admission and exhaust of fluid under pressure to and from said fluid pressure actuated means for reversing the carriage movement, a rotary spindle on which one of said members is mounted, other fluid pressure actuated means for controlling the rotation of said spindle, the admission and exhaust of fluid under pressure to and from said last means being controlled by the above-mentioned reversing valve for procuring cessation of rotation of the spindle at one end of the carriage movement, and other manually controlled valve means for controlling the admission and exhaust of fluid under pressure to said last fluid pressure actuated means for rendering said means inoperative, thereby procuring selectively either continuous rotation of said spindle or no movement of said spindle independently of the carriage movement.

8. In a machine of the class described, a tool member and a work-supporting member, a carriage on which one of said members is mounted, fluid pressure actuated means to procure reciprocation of said carriage for a relative movement between said members, reversing means including a reversing valve for controlling the admission and exhaust of fluid under pressure to and from said fluid pressure actuated means for reversing the carriage movement, a rotary spindle on which one of said members is mounted, other fluid pressure actuated means for controlling the rotation of said spindle, the admission and exhaust of fluid under pressure to and from said last means being controlled by the above-mentioned reversing valve for procuring cessation of rotation of the spindle at one end of the carriage movement, and manually controlled valve means for controlling the admission and exhaust of fluid to said last fluid pressure actuated means to procure cessation of the rotation of said spindle independently of said carriage movement and in any position of said carriage.

9. In a machine of the class described, a tool member and a work-supporting member, a carriage on which one of said members is mounted, fluid pressure actuated means to procure reciprocation of said carriage for a relative movement between said members, reversing means including a reversing valve for controlling the admission and exhaust of fluid under pressure to and from said fluid pressure actuated means for reversing the carriage movement, a rotary spindle on which one of said members is mounted, other fluid pressure actuated means for controlling the rotation of said spindle, the admission and exhaust of fluid under pressure to and from said last means being controlled by the above-mentioned reversing valve for procuring cessation of rotation of the spindle at one end of the carriage movement, and manually controlled valve means for procuring, selectively, rotation of said spindle or cessation of rotation of said spindle independently of the carriage movement and in any position of said carriage.

10. In a machine of the class described, a tool member and a work-supporting member, a carriage on which one of said members is mounted, fluid pressure actuated means to procure reciprocation of said carriage for a relative movement between said members, reversing means in-

- cluding a reversing valve for controlling the admission and exhaust of fluid under pressure to and from said fluid pressure actuated means for reversing the carriage movement, a rotary spindle on which one of said members is mounted, other fluid pressure actuated means for controlling the rotation of said spindle, the admission and exhaust of fluid under pressure to and from said last means being controlled by the above-mentioned reversing valve for procuring cessation of rotation of the spindle at one end of the carriage movement, and an additional valve means for controlling the rotation of the spindle so that the latter selectively may be started and stopped in response to movement of the carriage or may remain at rest independently of the carriage movement or may be continuously rotated independently of the carriage movement.
11. In a machine of the class described, a tool member and a work-supporting member, a carriage on which one of said members is mounted fluid pressure actuated means to procure reciprocation of said carriage for a relative movement between said members, reversing means including a reversing valve for controlling the admission and exhaust of fluid under pressure to and from said fluid pressure actuated means for reversing the carriage movement, a rotary spindle on which one of said members is mounted, other fluid pressure actuated means for controlling the rotation of said spindle, the admission and exhaust of fluid under pressure to and from said last means being controlled by the above-mentioned reversing valve for procuring cessation of rotation of the spindle at one end of the carriage movement, and an additional manually-controlled valve means to control the rotation of the tool member so that the latter, selectively, may rotate continuously independently of the carriage movement or may be started and stopped in response to said carriage movement.
12. In a machine of the class described, a tool member and a work-supporting member, a carriage on which one of said members is mounted, fluid pressure actuated means to procure reciprocation of said carriage for a relative movement between said members, reversing means including a reversing valve for controlling the admission and exhaust of fluid under pressure to and from said fluid pressure actuated means for reversing the carriage movement, a rotary spindle on which one of said members is mounted, other fluid pressure actuated means for controlling the rotation of said spindle, the admission and exhaust of fluid under pressure to and from said last means being controlled by the above-mentioned reversing valve for procuring cessation of rotation of the spindle at one end of the carriage movement, and an additional manually-controlled valve means to control the rotation of the spindle so that the latter may selectively remain at rest independently of the carriage movement or may be started and stopped in response to said carriage movement.
13. In a machine of the class described, a base having a reciprocatory carriage mounted thereon, rotary spindles mounted on said base adjacent opposite ends of said reciprocatory carriage, means to rotate the spindles adjacent one end of said base, other means for rotating the spindles at the opposite end of the base, fluid pressure means for actuating said carriage, means to control the rotation of said spindles in response to movement of said carriage, whereby the spindles at one end of said base are started and stopped at opposite ends of the carriage movement, and the spindles on the opposite end of the base are stopped and started at opposite ends of the carriage movement, with the spindles at either end of the carriage rotating only when the carriage is moving toward said spindles, and individual valve means for controlling the rotation of the spindles on opposite ends of the base, said valve means being arranged for manual movement to procure continuous operation of the spindles on either end of the base independently of said reciprocating carriage.
14. In a machine of the class described, a base having a reciprocatory carriage mounted thereon, rotary spindles mounted on said base adjacent opposite ends of said reciprocatory carriage, means to rotate the spindles adjacent one end of said base, other means for rotating the spindles at the opposite end of the base, fluid pressure means for actuating said carriage, means to control the rotation of said spindles in response to movement of said carriage, whereby the spindles at one end of said base are started and stopped at opposite ends of the carriage movement, and the spindles on the opposite end of the base are stopped and started at opposite ends of the carriage movement, with the spindles at either end of the carriage rotating only when the carriage is moving toward said spindles, and individual valve means for controlling the rotation of the spindles on opposite ends of the base, said valve means being arranged for manual movement to maintain said spindles at rest independently of the reciprocating carriage.
15. In a machine of the class described, a base having a reciprocatory carriage mounted thereon, rotary spindles mounted on said base adjacent opposite ends of said reciprocatory carriage, means to rotate the spindles adjacent one end of said base, other means for rotating the spindles at the opposite end of the base, fluid pressure means for actuating said carriage, means to control the rotation of said spindles in response to movement of said carriage, whereby the spindles at one end of said base are started and stopped at opposite ends of the carriage movement, and the spindles on the opposite end of the base are stopped and started at opposite ends of the carriage movement, with the spindles at either end of the carriage rotating only when the carriage is moving toward said spindles, and individual valve means for controlling the rotation of the spindles on opposite ends of the base, said valve means being arranged for manual movement to maintain said spindles at rest independently of the reciprocating carriage.
16. In a machine of the class described, a carriage having a normal reciprocatory stroke, reversing means including a reversing lever for reversing the carriage movement, reversing dogs on said carriage for shifting said lever at opposite ends of the carriage movement, thereby reversing the direction of movement of said carriage, manually positioned means on the reversing lever to render the reversing dog at one end of the stroke inoperative, said last means being manually positioned during the carriage movement, stop means to bring said carriage to rest at the end of its stroke when said manually-positioned means are inoperative, the subsequent return of said manually-positioned means to operative position rendering the corresponding reversing dog

and stopped at opposite ends of the carriage movement, and the spindles on the opposite end of the base are stopped and started at opposite ends of the carriage movement, with the spindles at either end of the carriage rotating only when the carriage is moving toward said spindles, and individual valve means for controlling the rotation of the spindles on opposite ends of the base, said valve means being arranged for manual movement to procure continuous operation of the spindles on either end of the base independently of said reciprocating carriage.

17. In a machine of the class described, a base having a reciprocatory carriage mounted thereon, rotary spindles mounted on said base adjacent opposite ends of said reciprocatory carriage, means to rotate the spindles adjacent one end of said base, other means for rotating the spindles at the opposite end of the base, fluid pressure means for actuating said carriage, means to control the rotation of said spindles in response to movement of said carriage, whereby the spindles at one end of said base are started and stopped at opposite ends of the carriage movement, and the spindles on the opposite end of the base are stopped and started at opposite ends of the carriage movement, with the spindles at either end of the carriage rotating only when the carriage is moving toward said spindles, and individual valve means for controlling the rotation of the spindles on opposite ends of the base, said valve means being arranged for manual movement to maintain said spindles at rest independently of the reciprocating carriage.

18. In a machine of the class described, a base having a reciprocatory carriage mounted thereon, rotary spindles mounted on said base adjacent opposite ends of said reciprocatory carriage, means to rotate the spindles adjacent one end of said base, other means for rotating the spindles at the opposite end of the base, fluid pressure means for actuating said carriage, means to control the rotation of said spindles in response to movement of said carriage, whereby the spindles at one end of said base are started and stopped at opposite ends of the carriage movement, and the spindles on the opposite end of the base are stopped and started at opposite ends of the carriage movement, with the spindles at either end of the carriage rotating only when the carriage is moving toward said spindles, and individual valve means for controlling the rotation of the spindles on opposite ends of the base, said valve means being arranged for manual movement to procure continuous operation of the spindles on either end of the base independently of said reciprocating carriage, and for other manual movement to maintain said spindles at rest independently of said reciprocating carriage.

19. In a machine of the class described, a carriage having a normal reciprocatory stroke, reversing means including a reversing lever for reversing the carriage movement, reversing dogs on said carriage for shifting said lever at opposite ends of the carriage movement, thereby reversing the direction of movement of said carriage, manually positioned means on the reversing lever to render the reversing dog at one end of the stroke inoperative, said last means being manually positioned during the carriage movement, stop means to bring said carriage to rest at the end of its stroke when said manually-positioned means are inoperative, the subsequent return of said manually-positioned means to operative position rendering the corresponding reversing dog

- operative for shifting the reversing lever to set the carriage again in operation.
17. In a machine of the class described, a tool member and a work-supporting member, a reciprocating carriage supporting one of said members to provide for a relative movement therebetween, means for actuating said carriage, including a fluid pressure source, a cylinder and piston, one of which is connected to the carriage, a reversing valve for alternately directing fluid under pressure from said source to opposite ends of the cylinder, and means including reversing dogs on the carriage and a pilot valve actuated thereby to procure a shifting movement of said reversing valve for reversing the direction of the carriage, said means also including bleed ports to permit shifting of the reversing valve only after a predetermined time interval subsequent to the shifting of said pilot valve.
18. In a machine of the class described, a tool member and a work-supporting member, a reciprocating carriage supporting one of said members to provide for a relative movement therebetween, means for actuating said carriage, including a fluid pressure source, a cylinder and piston, one of which is connected to the carriage, a reversing valve for alternately directing fluid under pressure from said source to opposite ends of the cylinder, and means for shifting said reversing valve at opposite ends of the carriage movement, said means including a pilot valve, means responsive to the carriage movement for shifting the position of said pilot valve, cylinders at opposite ends of the reversing valve, the latter being in the form of a plunger slideable in said cylinders, and small bleed ports to provide a connection from the fluid pressure source into the cylinders at opposite ends of said reversing valve, the pilot valve selectively cutting off the discharge of fluid from said cylinders.
19. In a machine of the class described, a tool member and a work-supporting member, a reciprocating carriage supporting one of said members to provide for a relative movement therebetween, a base for said carriage, fluid pressure means for actuating said carriage, means including reversing dogs on said carriage, and a valve, for reversing the direction of movement of the carriage at opposite ends of the carriage stroke, a slow-down valve for reducing the rate of travel of the carriage during the portion of its movement in one direction only, means on said carriage for actuating the slow-down valve and a latch to provide for actuation of said valve by said means during the movement of the carriage in one direction only said reversing means being operable while the slow-down valve is operative, and cooperating means on the carriage and base to stop the carriage at a predetermined point at each end of the carriage movement after shifting of said first valve.
20. In a machine of the class described, a base, a reciprocatory table on said base, rotary spindles on said base at opposite ends of said table, means to actuate said table comprising a pressure source, a cylinder and piston, one of which is connected to said table, and reversing means for alternately directing fluid under pressure from said source to opposite ends of the cylinder through connections between said reversing means and said cylinder, a throttle valve in each of said connections responsive to the table movement for rendering each throttle valve operative, and means accessible from the operator's position at the front of the machine for adjusting the throttling action of each of said throttle valves.
21. In a machine of the class described, a base, a reciprocatory table on said base, rotary spindles on said base at opposite ends of said table, means for actuating said table comprising a pressure source, a cylinder and piston, one of which is connected to said table, and reversing means for alternately directing fluid under pressure from said source to opposite ends of the cylinder through connections between said reversing means and said cylinder, a throttle valve in each of said connections, means on said table for actuating one of said throttle valves in one direction only of the table movement, other means on the table for actuating the other throttle valve in response to movement of the table in the opposite direction, and means for adjusting the throttling action of each of said valves independently, said last means being accessible from the operator's position at the front of the machine.
22. In a machine of the class described, a tool member and a work-supporting member, a reciprocating carriage supporting one of said members to provide for a relative movement therebetween, means for actuating said carriage, including a fluid pressure motor and a reversing valve actuated in response to the carriage movement for reversing the direction of movement thereof at opposite ends of the carriage stroke, and a throttle valve for reducing the rate of travel of the carriage during a portion of its movement in one direction only, said throttle valve being actuated directly in response to the movement of the carriage by an actuating member on said carriage, said throttle valve being arranged to decrease the flow of fluid therethrough in proportion to the extent of the valve movement.
23. In a machine of the class described, a tool member and a work-supporting member, a reciprocating carriage supporting one of said members to provide for a relative movement therebetween, means for actuating said carriage, including a fluid pressure motor and a reversing valve actuated in response to the carriage movement for reversing the direction of movement thereof at opposite ends of the carriage stroke, and a throttle valve for reducing the rate of travel of the carriage during a portion of its movement in one direction only, said throttle valve being actuated directly in response to the movement of the carriage by an actuating member on said carriage, said throttle valve being arranged to decrease the flow of fluid therethrough in proportion to the extent of the valve movement, and means independent of the actuating member for adjusting the maximum closing movement of said valve for controlling the minimum rate of travel of the carriage.
24. In a machine of the class described, a base, a reciprocatory table on said base, rotary spindles on said base at opposite ends of said table, means for actuating said table, comprising a pressure source, a cylinder and piston, one of which is connected to said table, and a reversing valve for alternately directing fluid under pressure from said source to opposite ends of the cylinder through connections between said reversing means and said cylinder, a throttle valve in each of said connections, each of said throttle valves being actuated by said table in one direction only of the table movement, and additional means comprising a cylinder and piston unit for the spindles at each end of the table for controlling

the rotation thereof, said cylinder and piston units being connected to the reversing valve for starting and stopping of the spindle at opposite ends of the carriage movement, and manually controlled valve members for separately rendering each of said cylinder and piston units independent of the reversing valve for continuous rotation of the spindle at either end of the table.

25. In a machine of the class described, a carriage actuated by fluid under pressure, reversing means including a reversing lever for procuring a reciprocatory movement of said carriage, reversing dogs on said carriage for engagement with said reversing lever at opposite ends of the carriage stroke for actuating said lever in response to movement of said carriage, a dog engaging member carried by said reversing lever, and manually controlled means on said reversing lever for shifting said dog engaging member into inoperative position to render either of the reversing dogs selectively inoperative.

26. In a machine of the class described, a carriage actuated by fluid under pressure, reversing means including a reversing lever for procuring a reciprocatory movement of said carriage, reversing dogs on said carriage for engagement with said reversing lever at opposite ends of the carriage stroke for actuating said lever in response to movement of said carriage, a dog engaging member carried by said reversing lever, manually controlled means on said reversing lever for shifting said dog engaging member into inoperative position to render either of the reversing dogs selectively inoperative, and means to bring said carriage to rest at the end of its movement when the reversing dog is rendered inoperative.

27. In a machine of the class described, a carriage actuated by fluid under pressure, reversing means including a reversing lever for procuring a reciprocatory movement of said carriage, reversing dogs on said carriage for engagement with said reversing lever at opposite ends of the carriage stroke for actuating said lever in response to movement of said carriage, a dog engaging member carried by said reversing lever and manually controlled means on said reversing

lever for shifting said dog engaging member into inoperative position to render either of the reversing dogs selectively inoperative, return of said dog engaging member to original position procuring movement of said reversing lever for a movement of the carriage in the opposite direction.

28. In a machine of the class described, a carriage actuated by fluid under pressure, reversing means including a reversing lever for procuring a reciprocatory movement of said carriage, reversing dogs on said carriage for engagement with said reversing lever at opposite ends of the carriage stroke for actuating said lever in response to movement of said carriage, a dog engaging member carried by said reversing lever, manually controlled means on said reversing lever for shifting said dog engaging member into inoperative position to render either of the reversing dogs selectively inoperative, and 20 cooperating positive abutment means for bringing said carriage to rest at the end of its movement when the reversing dog is rendered inoperative, return of said dog engaging member to original position after said carriage comes to 25 rest procuring shifting movement of said reversing member.

29. In a boring machine, a base, a tool member and a work-supporting member, a table on which one of said members is mounted, fluid pressure 30 means for reciprocating said table, including a cylinder and piston, one of which is connected to the table, a source of fluid under pressure, a valve for directing fluid under pressure alternately to opposite ends of the cylinder, and means for shifting said valve, including reversing dogs on the table, a pilot valve actuated thereby, connections from said pilot valve to the main valve for shifting said valve in response to movement of said pilot valve, at least one of said connections being arranged to procure the admission of fluid to said main valve at a slow rate whereby the table is reversed a predetermined time subsequent to the actuation of the pilot valve by the reversing dog. 40

WILLIAM D. SCHMIDT. 45

CERTIFICATE OF CORRECTION.

Patent No. 2,174,044.

September 26, 1939.

WILLIAM D. SCHMIDT.

It is hereby certified that error appears in the printed specification of the above numbered patent requiring correction as follows: Page 1, first column, line 44, for "objectional" read objectionable; line 55, after the word "valve" insert with an arrangement to cause shifting movement of the main valve; page 2, first column, line 9, for "spindles on" read spindles in; page 5, second column, line 27, for "and bridge" read hand bridge; and that the said Letters Patent should be read with this correction therein that the same may conform to the record of the case in the Patent Office.

Signed and sealed this 11th day of November, A. D. 1939.

(Seal)

Henry Van Arsdale,

Acting Commissioner of Patents.
